UNITED STATES PATENT OFFICE.

FRANK C. SHERMAN, OF ROCHESTER, NEW YORK, ASSIGNOR TO EASTMAN KODAK COMPANY, OF ROCHESTER, NEW YORK, A CORPORATION OF NEW YORK.

PHOTOGRAPHIC-PRINT-WASHING MACHINE.

Application filed September 29, 1922. Serial No. 591,375.

To all whom it may concern:

Be it known that I, FRANK C. SHERMAN, a citizen of the United States of America, residing at Rochester, in the county of Monroe and State of New York, have invented certain new and useful Improvements in Photographic-Print-Washing Machines, of which the following is a full, clear, and exact specification.

10 This invention relates to photography and more particularly to a machine for washing photographic prints. One of the objects of my invention is to provide a machine in which prints will be washed by a rotating 15 drum suspended in a tank of water; another object is to provide a simple suspension device for the drum; another object is to provide a driving mechanism for the drum which is automatically moved from its operative position in contact with the drum 20 when the latter is moved from the solution tank; and other objects will appear from the following specification, the novel features being pointed out in the claims at the end 25 thereof.

Fig. 1 is a perspective of a machine constructed in accordance with, and illustrating one embodiment of my invention;

Fig. 1^A is a detail side view of the latching link;

Fig. 2 is a partial side elevation of the drum and drive lifting mechanism, parts being shown in broken lines;

Fig. 3 is a top plan view of the machine, 35 a part being shown in section and the driving mechanism being removed;

Fig. 4 is a top plan of the driving mechanism; and

Fig. 5 is a detail view showing a partial 40 side elevation of the driving mechanism.

This machine consists of a tank 1 for holding the wash water, equipped with a suitable water inlet (not shown) and a water exit 2. This tank is carried by supports 3 at one end and 4 at the other, these parts forming a base. Member 4 is provided with bearings 5 and 6, and member 3 with a single bearing 7 in alignment with bearing 6.

50 A drum 8 is provided with trunnions 9 and 10 by which it is suspended, and is equipped with a door 11 hinged at 12 to the drum. Latches 13 are for holding the door shut, in this case formed of U-shaped members slideable to and from the locking position shown in Fig. 1. In Fig. 3 two small

hinges 12' 12' are used in place of the piano hinge 12 of Fig. 1.

The trunnions 9 and 10 are preferably carried by ball bearings 14 which rest on one side in seat 15 of the lever arm 16, and on the other side in seat 17 of arm 18. Arm 18 is pinned at 19 to a shaft 20 mounted to turn upon the set pins 21 and 22 which pass through the bearing seats 6 and 7. Arm 18 has an extension 23 resting on an edge 24 of the tank. Lever 16 is also pinned at 24' to shaft 20, and extends forwardly across the tank terminating in a handle 25. A shield 26 protects the hand of an operator from being caught between handle 25 and an edge 27 of the tank upon which lever 16 rests. It is obvious that by raising the handle, as shown by arrows, Fig. 2, the drum 8 is raised, as lever 16 raises trunnion 10 as it turns shaft 20, which in turn causes arm 18 to raise trunnion 9, these parts forming, in effect, a drum suspending frame hinged to support 4.

55 Lever 16 is held in raised position by means of a latch consisting of a link 28 pivoted to the lever at 29 and movable between two studs 30 and 31 in a wall 32 of the tank. These studs are headed to guide the link, and one stud 30 is adapted to engage the notch 33 in link 28 when in the position shown in Fig. 1^A. To lower drum, raise lever 16 slightly and, holding link 28 towards the front of the machine, lower the lever; this disengages the slot 33 from pin 30, permitting the link to slide between the studs.

60 The drum is rotated through the following mechanism. A motor is positioned beneath shield 35, the pulley 36 being mounted on the motor shaft 37. Pulley 38 connected to pulley 36 by a belt 39 drives a stub shaft 40 (Fig. 5) carried by bearing 5 of the casting 4. This shaft drives pulley 41, and carries an arm 42 which, however, is freely movable thereon, forming a hinged connection to the support 4. A belt 43 connects pulley 41 to another pulley 44 mounted on shaft 45'. Pulley 44 is affixed to the driving member 45, which in this instance is equipped with rubber friction bands 46-46', for contacting with the smooth periphery 47 of drum 8. An extension 48 may be provided to limit the rearward movement of arm 42 by striking the washer 49 mounted on shaft 20 (Fig. 5).

65 The driving member 45 rests upon, and 105

frictionally drives the drum when lowered upon it, but when raised it is raised from contact with the drum by a link 50 connecting arm 42 to lever 16. This link is fastened to lever 16 by means of a pin 29 passing through link 28 as well as link 50, and the lug 52 which forms a part of lever 16. As can readily be seen from Fig. 2, the arrangement of the pivotal points carrying the drum and the drive is such that as the handle is moved from the position shown in Fig. 2 to that shown in Fig. 1, the extent of movement of the driving wheel 45 is greater than that of the drum periphery 47 so that the driving connection is broken during the first part of the upward movement. The drive wheel 45 is continuously driven by the belt 43 in all positions, but is in operative position to drive the drum only when lowered into contact therewith by handle 25. Only one motion is, therefore, necessary to raise the drum and automatically disengage the driving connection.

The operation of the machine is very simple. When in position shown in Fig. 1, the prints to be washed are loaded through the door 11 into the drum 8, and, after unlatching link 23, handle 25 is lowered causing the drum to become partially submerged in tank 1 and simultaneously causing the driving wheel 45 to frictionally engage and rotate the drum. When washing is complete, the handle is raised and the prints removed through the door.

Having thus described my invention, what I claim as new and desire to secure by Letters Patent is:

1. A photographic print washing machine comprising a tank, a movable washing device, means for suspending the washing device in the tank including a frame movable to raise the washing device to a loading position, a driving mechanism, a movable mount carrying the driving mechanism adapted to move it to and from its operative position in which it moves the washing device, and means for moving the driving mechanism from its operative driving position as the washing device is moved toward its loading position.

2. A photographic print washing machine comprising a tank, a washing device, a frame for suspending the washing device in the tank in a washing position being movable so that the washing device may be raised to a loading position, a driving mechanism for said washing device, a movable arm carrying the driving mechanism movable to and from an operative position in which it transmits motion to the washing device, and a connection between the movable frame and arm whereby the driving mechanism is operatively positioned to move the washing device only when the latter is in its washing position.

3. A photographic print washing mechanism comprising a tank, a drum adapted to be suspended therein, a lever adapted to raise and lower the drum to and from a washing position, a drum driving mechanism movably mounted above the drum, and means connected to the handle and the drum driving mechanism for moving the latter to its driving position as the drum is moved to its washing position.

4. A photographic print washing machine comprising a tank, a rotary drum suspended therein, means for suspending the drum including a handle adapted to move the drum to and from its washing position in the tank, a movable member carrying a drum driving element, and means operated by the handle, for raising the drum from its washing position and simultaneously raising the drum driving element from the drum.

5. A photographic print washing machine comprising a tank, a rotary drum suspended therein, a movable drum suspending frame, by which the drum may be moved to and from an operative position, a driving element, and means for moving the driving element to and from an operative position in which it rotates the drum, and means for simultaneously moving the drum and driving element, causing them to rotate together when the drum is in its washing position, and causing the driving element to be moved from its operative position when the drum is moved from its washing position.

6. A photographic washing machine, comprising a tank, a rotatable drum suspended therein, a frame for carrying the drum in a washing position in the tank and in a raised loading position, a friction wheel adapted to contact with and drive the drum, a movable member carrying the friction wheel, a link between the drum carrying frame and the movable member carrying the friction wheel whereby the latter is moved out of contact with the drum when the drum suspending frame is moved from the washing position.

7. A photographic washing machine comprising a tank, a drum, a frame for suspending the drum in the tank in an operative washing position, being movable to move the tank to an inoperative or loading position, a drum driving mechanism, a movable arm carrying the mechanism adapted to move it to and from an operative position in which it drives the drum, and means for moving the frame and arm together so that the parts carried by these members will move to their operative and inoperative positions simultaneously.

8. A photographic washing machine comprising a washing tank, a washing drum suspended therein, means for rotating the washing element including a friction driving wheel adapted to contact with the drum,

- a hinged member adapted to carry the friction driving wheel to and from its operative position in contact with the drum, means for raising the drum to a loading position, there being connections between the driving wheel and the drum raising means adapted to raise the driving wheel when the drum is raised, moving it out of driving contact with the revolute drum.
9. In a photographic print washing machine comprising a support, a tank carried by the support, a drum revolubly suspended therein, a frame for carrying the drum hinged to the support adapted to move the drum to and from a washing position, a driving means, an arm carrying the driving means hinged to the support, the driving means being operatively positioned to drive the drum when the latter is in its washing position, connections to the hinged drum frame and the hinged arm carrying the driving means to move each simultaneously, the

hinged members being arranged so that the extent of movement of the driving means is greater than that of the drum. 25

10. A photographic print washing machine comprising a tank, a drum suspended therein, a frame for suspending the drum including a handle adapted to move the drum to and from a loading position, a movable arm, a drum driving element mounted thereon, and means operated by the handle for raising the drum to its loading position and at the same time moving the arm carrying the drum driving element so as to cause the driving element to move from the drum, and a supporting link extending between the tank and the drum frame for holding the movable mechanism when the drum is in its loading position. 30 35 40

Signed at Rochester, New York, this 25th day of Sept. 1922.

FRANK C. SHERMAN.
